(57) **CLAIM**

The ornamental design for a handheld game console, as shown and described.

DESCRIPTION

FIG. 1 is a bottom, front and right side perspective view of a handheld game console, showing my new design; FIG. 2 is a top, rear and left side perspective view thereof; FIG. 3 is a front view thereof; FIG. 4 is a rear view thereof; FIG. 5 is a left side view thereof; FIG. 6 is a right side view thereof; FIG. 7 is a top view thereof; and, FIG. 8 is a bottom view thereof. The broken lines in the drawings depict portions of the handheld game console that form no part of the claimed design.
